US00D856977S

(12) **United States Design Patent** (10) Patent No.: **US D856,977 S**
(45) Date of Patent: **** Aug. 20, 2019**

(54) **SPEAKER COVER**

(71) Applicant: **SpaceControl GmbH & Co. KG**,
Seefeld (DE)
(72) Inventor: **Volker Hartmann**, München (DE)
(73) Assignee: **SPACECONTROL GMBH & CO.**
KG, Seefeld (DE)

(**) Term: **15 Years**

(21) Appl. No.: **29/612,417**

(22) Filed: **Aug. 1, 2017**

(30) **Foreign Application Priority Data**

Feb. 1, 2017 (DE) 40 2017 000 105

(57) **CLAIM**

The ornamental design for a speaker cover, as shown herein.

DESCRIPTION

FIG. 1 is a front perspective view of a speaker cover in accordance with the present invention;
FIG. 2 is a rear perspective view of the speaker cover of FIG. 1;

FIG. 3 is a front view of the speaker cover of FIG. 1;
FIG. 4 is a rear view of the speaker cover of FIG. 1;
FIG. 5 is a front side view of the speaker cover of FIG. 1;
FIG. 6 is a back side view of the speaker cover of FIG. 1;
FIG. 7 is a left side view of the speaker cover of FIG. 1; and,
FIG. 8 is a right side view of the speaker cover of FIG. 1.

1 Claim, 8 Drawing Sheets
